PUSHING AND PULLING IMPLEMENT

Guy A. Countryman, Ashland, Ohio

Application April 20, 1932. Serial No. 606,458

1 Claim. (Cl. 254—100)

This invention pertains to an improvement in pushing and pulling implements, and more particularly to a repair tool or implement to be used in reshaping damaged automobiles. It is the principal object of the invention to provide a device of the above mentioned character, adapted to be used for reshaping the dented body of an automobile and straightening the twisted frame, particularly the bent front and rear horns thereof.

Generally considered, the invention comprises a relatively short main body portion in the form of a lifting jack, adapted to impart pushing and pulling forces to screw threaded extensions connected to and in axial alignment with the relatively movable parts of the jack.

It is a more specific object of this invention to provide a device of the above mentioned character wherein the coacting extensions are of improved construction and so mounted on the main jack that they can be conveniently interchanged, thus adapting the tool to the particular repair job desired.

Other objects, as well as the nature, characteristic features and scope of this invention will be more readily apparent from the following description taken in connection with the accompanying drawings and pointed out in the claim, forming a part of this specification.

In the drawings:

Figure 1 is a side elevation of the bent front horn of an automobile showing the repair tool applied in operative position;

Figure 2 is a sectional view on line 2—2 of Figure 1;

Figure 3 is a sectional view on line 3—3 of Figure 1;

Figures 4, 5, 6 show sectional views of the individual parts of the tool shown in Figure 1;

Figure 7 is a side elevation of the tool shown in Figure 1 provided with extensions of special length and shape, including an extensible member to adapt the tool to body reshaping work;

Figure 8 is a longitudinal sectional view through the tool shown in Figure 7;

Figure 9 is an enlarged detail view of the ratchet mechanism of the main jack operating means; and

Figure 10 is an enlarged sectional view of the interlocking means for the members of the extensible member or extension of the tool shown in Figure 7.

Similar characters of reference are employed in all of the above described views, to indicate corresponding parts.

Referring now more particularly to the accompanying drawings, and with special reference to Figures 1 to 6 inclusive, A denotes a main jack member or portion of familiar design, comprising a hollow casing or base 2 and a screw member 3, slidably mounted within the casing but held against rotary movement by means of a key 4, the ends of which travel in grooves 5. Threadedly mounted upon the screw member 3, and housed within the bulged or chambered portion 6 of the 60 casing 2 is a nut 7, formed with bevel teeth 7'. As the nut 7 is confined between the opposing walls 8—8' of the chambered portion of the casing against relative longitudinal movement on the screw member 3, rotation of the nut causes 70 member 3 to slide either in or out with respect to the casing, according to the direction of rotation of the nut. A bevel gear 9 mounted on stud shaft 10, and in mesh with the teeth 7' of nut 7, is provided with an operating crank 11, for rapid rotation of gear and nut, while a ratchet lever 12 also mounted on stud shaft 10 is used by the operator where a more powerful and step by step rotation of gear and nut is desired during spreading operations. A pawl 13 pivotally mounted on lever 75 12, as at 14, is normally held in operative engagement with the teeth of gear 9 by means of a spring 14'.

The jack member A is provided with coupling members or extensions 15 and 16 at its opposite 80 ends for respectively connecting the ends of the device with the horn or end 17 of an automobile frame 18 and the spring supporting shackle 19 depending from the frame. Extension 15, preferably of tubular form, is exteriorly threaded at 85 20 for engagement with the internally screw threaded end 21 of the jack, whereas the extension 16 is interiorly threaded at one end 22 for engagement with the outer enlarged threaded end 23 of screw member 3. The coupling extension 90 members 16 and 15 are pivotally supported by bolts 24 and 25 which connect these parts to the frame end 17 and spring supporting shackle 19 respectively, which bolts pass through perforations 27 formed in the coupling extension members 95 for this purpose.

The tool just described is particularly adapted for reshaping the bent horns of automobile frames, it merely being necessary for the operator to attach the tool between the spring supporting 100 connections of the frame and the horn, and thereafter extend or spread the tool by the operation of jack A.

Where the tool is to be used for straightening the body or fenders of an automobile, the mem- 110

bers 15 and 16 are unscrewed, and other members of somewhat different form substituted, such as shown in Figures 7, 8 and 10. In these figures an elongated tubular extension 28 screwed into the 5 base end 17 of jack A carries at its free end a readily detachable V-shaped interchangeable head 29, and connected to screw member 3 by means of a coupling 30, is a screw rod member or extension 31. Slidably mounted for relative longitudinal movement on the screw member 31 is 10 a headed sleeve 32, which sleeves over the member 31, and is fixed at its inner end to a clutch or ratchet housing 33, also longitudinally movable on screw member 31. Rotation of the sleeve 32 and housing 33 is prevented by means of a key 34, 15 extending from a wall of the housing into a key way 35, in screw member 31.

A pair of oppositely disposed threaded clutch or ratchet-lever members 36 and 37 pivotally mounted on pins 38 and 39 extending through 20 housing 33, serve to operatively connect the screw member 31, sleeve 32 and housing 33 together. The free ends of members 36 and 37 extend in opposite directions longitudinally of screw member 31, and their toothed inner faces 40 and 41 are pressed to interlocking engagement with the threads of member 31 by springs 42 and 43. Handles 44 and 45 secured to the free ends of the pawl members and extending outwardly through 25 slots 46-47 in the housing permit of one or both of the ratchet members 36-37 being manually rocked out of engagement with the member 31. As these ratchet members are mounted to pivot in opposite directions, it will be seen that each 30 member will lock the sleeve 32 against longi- 35

tudinal movement in one direction, while permitting free movement thereof in the opposite direction. Thus, when ratchet member 37 is manually moved on its pivot 39 to disengaged position, the sleeve 32 can be freely shifted in the direction of or toward jack member A, but will be locked against movement in an opposite direction by ratchet lever 36. Conversely when the lever 36 is disengaged from screw 31 by manually rocking the former on its pivot 38, the sleeve 32 can be moved in a direction away from the jack, but not toward the jack. It will thus be seen that the clutch mechanism enables the operator to quickly adjust the tool to any desired length, whereupon the main jack portion A may be operated in the manner previously described. 80 85 90

Having thus described my invention what I claim is:

In an automobile repair tool provided with an axially extended jack portion adapted to be used 95 as an individual jack, an extension embodying a screw rod and a sleeve member slidably and non-rotatably interengaged with each other, and coupling means for said rod and sleeve member provided with oppositely arranged locking ratchet members in engagement with the threads of said 100 rod for quick adjustment of said sleeve with respect to said screw rod, said ratchet members having their ratchet levers arranged to lock said sleeve member against movement in opposite directions, to promote quick adjustment of said 105 sleeve member in either direction by actuation of one or the other one of said ratchet levers. 100 105 110
